Primary Examiner—B. J. Bullock

[57] CLAIM

The ornamental design for a garment hanger, as shown and described.

DESCRIPTION

FIG. 1 is a front elevational view of a garment hanger showing my new design, the rear being substantially a mirror image;

FIG. 2 is a bottom plan view thereof;

FIG. 3 is a top plan view thereof;

FIG. 4 is a right side elevational view thereof, the left side being substantially a mirror image.
